Filed Jan. 18, 1962, Ser. No. 68,364

Term of patent 14 years

(Cl. D34—5)

FIG. 1

FIG. 2

FIGURE 1 is a top plan view of a game board showing my new design.

FIGURE 2 is an edge view thereof.

The characteristic feature of my design resides in the combination on the cruciform patterned game board disclosed of four raised finger-shaped inner home pathways and lined peripheral crosses, all as shown.

The dominant features of my new design reside in the portions shown in full lines.

I claim:

The ornamental design for a game board, as shown and described.
